UNITED STATES PATENT OFFICE

MAX R. LEHMAN, OF QUINCY, ILLINOIS, ASSIGNOR TO ORBON STOVE CO., OF BELLEVILLE, ILLINOIS, A CORPORATION OF DELAWARE

DESIGN FOR A STOVE CASING

Application filed October 31, 1929. Serial No. 33,239. Term of patent 14 years.

To all whom it may concern:

Be it known that I, MAX R. LEHMAN, a citizen of the United States, residing at Quincy, county of Adams and State of Illinois, have invented a new, original, and ornamental Design for Stove Casing, substantially as shown in the accompanying drawing.

The figure is a perspective view of the stove casing, showing my new design.

The linings for colors indicate that the colors of the surfaces so lined contrast with the colors of adjacent surfaces.

I claim:

The ornamental design for a stove casing as shown and described.

MAX R. LEHMAN.
